United States Patent Office.

JOHN WESTOVER, OF TAYLOR, ILLINOIS.

Letters Patent No. 80,103, dated July 21, 1868.

IMPROVED ELEVATOR.

The Schedule referred to in these Letters Patent and making part of the same.

TO WHOM IT MAY CONCERN:

Be it known that I, JOHN WESTOVER, of Taylor Post-Office, in the county of Ogle, and State of Illinois, have invented a new and useful Improvement in Elevators; and I do declare that the following is a true and accurate description thereof, reference being had to the accompanying drawings, and to the letters of reference marked thereon, and being a part of this specification, in which like letters indicate like parts in each figure.

Figure 1 is a top view.

Figure 2 is a side elevation.

Figure 3 is a front view of the extension-arm.

Figure 4 is a bottom view of the same.

The nature of my invention consists in constructing an elevator, for the purpose of raising a wagon-box or hay-rack filled with grain, hay, straw, or other heavy material, in the field, for building stacks equally as well as in the barn, for the purpose of raising hay to the level of the bays, and is easily moved from place to place, being provided with adjustable wheels for that purpose.

To construct my apparatus, I build a frame, A, surmounted by the platform B, upon which I erect the standards C, at the top of which I place the sheaves D.

E are side-timbers, secured to the standards C, in the front of which is journaled the shaft F, at the centre of which is secured the ratchet-drum G, held in position by the pawl H, and secured by the stop I.

J are wheels, revolving upon proper axles in the pedestals K pivoted to the rear ends of the side-timbers E. These pedestals are secured in an upright position by means of the pins L when it is desired to move the apparatus.

M are horizontal rods, provided with guides, N, sliding in grooves in the standards C.

O are guide-pulleys at the sides of the two rear standards.

P are elevating-ropes, secured to the horizontal rods M, and running over the sheaves D, the two rear ones also under the guide-pulleys O, and wound upon the shaft F by unwinding the drag-rope Q from the drum G, and to which the team is attached by means of a proper hook or other device.

R are transverse extension-arms, which are intended to form the base of a hay-rack, or may be secured to a wagon-box by proper hooks, and are so constructed that by means of the crossed cords running over suitable pulleys, and secured alternately to the inner ends of the extension-arms R¹ and R², when either of them is drawn out or retired, the corresponding one is caused to advance or retire at the same time.

To operate my apparatus, we will suppose it to be placed alongside of a hay-stack in course of erection. The wagon, represented in the drawings by the block of wood S, is surmounted by a hay-rack, resting upon the extension-arms R, is drawn upon the platform B; the horses straddling the drum G as they pass off, stopping immediately after passing off, which will bring the double-trees directly over the drum. The double-trees are then detached from the tongue of the wagon, and attached to the hook on the drag-rope Q. The sliding arms R¹ and R² are then drawn out so as to project over the horizontal bars M. The team is then driven ahead. As the drag-rope unwinds from the drum G, the elevating-ropes P are wound upon the shaft F, and the rack, with its load, is elevated to the desired height, the pawl H retaining the drum G in its position, and, if necessary, the stop I may be used to insure greater safety.

After the hay is unloaded from the rack to the top of the stack, by throwing the pawl H out of gear, the rack will be lowered on to the wagon, by its own weight; as the team is backed up; the drag-rope Q being re-wound upon the drum G, ready for elevating the next load.

This apparatus serves equally as well for elevating hay or straw in the barn, being placed on the floor between the "bays." To move it from place to place, the rear end is slightly elevated, bringing the pedestals K to a vertical position, where they are secured by the pins L. The front end of the machine may be secured to the rear axle of a wagon, or rest upon the rear end of the box, when the whole may be moved with ease.

What I claim as my invention, and desire to secure by Letters Patent, is—

1. The extension-arms R¹ and R², in connection with any suitable hay-rack or wagon-box, when used for the purposes herein described and set forth.

2. The combination and arrangement of the frame A, platform B, standards C, provided with sheaves D and guide-pulleys O, the side-timbers E, pedestal K, wheels J and pins L, the shaft F, drum G, pawl H, stop I, horizontal bars M, guides N, elevator-ropes P, and drag-ropes Q, in connection with the extension-arms R¹ and R², when constructed, arranged, and operating substantially as described, and for the purposes herein set forth.

JOHN WESTOVER.
